BRIDLE BIT MOUTHPIECE

Leslie F. Garcia, P.O. Box 1966, Reno, Nev. 89505,
and Larry R. Parkison, 6950 Longridge Ave., North
Hollywood, Calif. 91605

Filed Apr. 19, 1973, Ser. No. 352,622

Term of patent 14 years

Int. Cl. D30—04

U.S. Cl. D30—21

FIG. 1 is a front elevational view of a bridle bit mouthpiece, showing our new design;

FIG. 2 is a rear elevational view;

FIG. 3 is a bottom plan view;

FIG. 4 is a top plan view; and

FIG. 5 is a right side elevational view, the left side elevational view being in mirror symmetry.

We claim:

The ornamental design for a bridle bit mouthpiece, as shown.
